US00D533064S

(12) **United States Design Patent** (10) **Patent No.:** **US D533,064 S**
Glynn et al. (45) **Date of Patent:** **** Dec. 5, 2006**

(54) **CONTAINER**

(75) Inventors: **Nigel Joseph Glynn**, Middlesex (GB);
Jennifer Claire Morton, Berkshire (GB); **Craig Elliot Pirie**, Greenwich, CT (US)

(73) Assignee: **The Procter & Gamble Company**, Cincinnati, OH (US)

(**) Term: **14 Years**

(21) Appl. No.: **29/206,508**

(22) Filed: **Jun. 1, 2004**

(51) LOC (8) Cl. **09-01**

(52) U.S. Cl. **D9/500**

(58) Field of Classification Search D9/435, D9/452, 500, 502–505, 509, 513, 515–516, D9/537–539, 545, 549, 558, 686, 698–691; D7/300.1, 510–511, 602, 612; D11/143, 146, D11/152–154; 215/381–385

See application file for complete search history.

(57) **CLAIM**

The ornamental design for a container, as shown and described.

DESCRIPTION

FIG. 1 is a perspective view of a first embodiment for a container showing our new design;

FIG. 2 is a bottom plan view thereof;

FIG. 3 is a top plan view thereof;

FIG. 4 is a front elevational view thereof;

FIG. 5 is a perspective view of a second embodiment for a container showing our new design;

FIG. 6 is a bottom plan view thereof;

FIG. 7 is a top plan view thereof;

FIG. 8 is a front elevational view thereof;

FIG. 9 is a perspective view of a third embodiment for a container showing our new design;

FIG. 10 is a bottom plan view thereof;

FIG. 11 is a top plan view, thereof;

FIG. 12 is a front elevational view thereof;

FIG. 13 is a perspective view of a fourth embodiment for a container showing our new design;

FIG. 14 is a bottom plan view thereof;

FIG. 15 is a top plan view thereof; and,

FIG. 16 is a front elevational view thereof.

The broken lines shown in the drawings are for illustrative purposes only and form no part of the claimed invention.
